FIG. 3.

JOHN O. BOYLE INVENTOR

By *Victor G. Evans*

ATTORNEY

UNITED STATES PATENT OFFICE.

JOHN O. BOYLE, OF YOUNGWOOD, PENNSYLVANIA.

CASTING DEVICE.

Application filed June 25, 1923. Serial No. 647,699.

To all whom it may concern:

Be it known that I, JOHN O. BOYLE, a citizen of the United States, residing at Youngwood, in the county of Westmoreland 5 and State of Pennsylvania, have invented new and useful Improvements in Casting Devices, of which the following is a specification.

This invention relates to casting devices, 10 and more particularly to a device specially adapted for use in dental work for casting "inlays" and other articles for use in dentistry. As this general method of casting is well known in this art it is necessary to give 15 but a brief description of this method. In practice, an impression is taken in wax or other suitable material of a cavity for which it is desired to cast a filling, after which this model is placed in a suitable flask which 20 is then filled with investment material, this material being a composition of plaster of Paris and other materials of a refractory nature. Suitable openings being provided, the investment material, which has been cast 25 in the form of a ring or cylinder, is then heated to melt and drive out the wax, after which metal in molten condition is caused to flow into the resulting cavity or hollow this metal, when set, reproducing the cavity 30 from which the wax impression was originally made.

One of the main objects of the invention is to provide simple and efficient means whereby the investment ring may be held 35 so as to be whirled about a horizontal axis thus forcing the molten metal, by centrifugal force, into the recess or cavity of the ring thus insuring the production of a casting of great density and which is an accurate 40 reproduction of the cavity from which the wax impression was originally taken. A further object is to provide a device of this character which will readily accommodate investment rings of different sizes. Another 45 object is to provide a device which will effectually prevent spilling of the molten metal in the event that some of it is displaced from the investment ring. Further objects will appear from the detail description.

50 In the drawings:—

Figure 1 is an elevation of the device, partly in section;

Figure 2 is a top plan view;

Figure 3 is a section taken substantially 55 on line 3—3 of Fig. 1;

Figure 4 is a top plan view of one of the holding rings;

Figure 5 is a top plan view of a larger size holding ring.

My device is more particularly adapted 60 for use in connection with an investment ring or cupel A formed of refractory material, this cupel being provided in its upper face with a depression a from the center of which extends a bore or sprue hole a'. In 65 its under face cupel A is provided with a recess b somewhat larger than recess a, this recess being adapted for reception of a mould or impression of a cavity, after which recess b is filled by a suitable investment material 70 c. After this has been done the cupel A may be heated in any suitable or preferred manner so as to melt the material of the mould and vaporize it, thus leaving the mould cavity c' with which sprue hole a' communi- 75 cates. The cupel A and the investment material c are refractory and combine to provide simple and efficient means for casting an article corresponding with the shape of recess c'.

My invention consists more particularly in the provision of a container 1 having a downwardly tapering body 2 provided with a depending neck 3 the lower end of which is closed by a bottom 4. An annular groove 5 is provided in neck 3 adjacent to the upper end thereof, and the neck is provided with a relatively short slot 6 extending from this groove and disposed oppositely to a relatively long slot 7 extending from the groove. 90 Slot 6 receives an outwardly projecting loop 8 provided at the central portion of a spring wire ring 9 the terminal portions of which overlap and are provided with outwardly projecting fingers 10 which extend through slot 7. By forcing fingers 10 toward each other ring 9 may be expanded or opened up to fit into groove 5 so as to permit cupel A to be readily inserted through this ring, the cupel resting upon bottom plate 4 as in Figure 1. After this has been done, by releasing fingers 10 ring 9 closes about and grips the cupel so as to prevent accidental loss of the same from the container 1. After this has been done, the metal which it is desired to 105 cast, such as gold, is placed in recess a of cupel A and is fused by a blow-pipe, the upper portion of the cupel serving as a crucible for this purpose. As the gold is fused it will run through the sprue opening a', into 110

recess c' , to a certain extent, but to insure a casting of the proper density and which accurately reproduces the original mould or impression, the metal should be forced under 5 appreciable pressure through sprue hole a' into recess c' . For this purpose the container 1 is whirled about a horizontal axis, the metal being pressed by centrifugal force through the sprue opening into the casting 10 recess.

To permit container 1 to be readily whirled, I provide this container with two diametrically opposite ears 11 through which are secured the ends of a bail 12 provided with a central loop 13. A chain 14 is secured through loop 13 in any suitable or preferred manner, this chain being secured to a ring 15 which is mounted to turn about a collar 16 secured on a handle 20 17 which tapers toward the ring, ring 15 being held against movement beyond the smaller end of the handle by a disc 18 secured by a screw 19 to the smaller end of handle 17, this disc being of greater diameter than the interior diameter of ring 15. By holding handle 17 and imparting a gyratory movement thereto, the container 1 may be whirled about a substantially horizontal axis at high speed so as to 25 force the molten metal into the casting recess c' in the manner previously described. The container 1 is preferably provided with two outwardly projecting lugs 20 positioned midway between ears 11, these lugs serving to support bail 12 in horizontal position to prevent over-heating or warping of the bail during fusing of the metal, while holding the bail in a readily accessible position. In Figures 1, 3 and 4 I have shown a small 30 sized cupel and ring. For a larger sized cupel I use the ring illustrated in Figure 5, the groove 5 of neck 3 being intended more particularly to accommodate this larger size of ring.

45 It will be seen that I have provided very simple and highly efficient means whereby the cupel or investment ring, as it is frequently called, is effectually held in the container during swinging or rotation thereof, and the downwardly tapering body 2 of the container serves to effectually prevent accidental spilling from the device of metal which may flow out of the cupel. In the event that any metal should be spilled from 50 the cupel, loss of this metal or possible injury to the user of the device, will be prevented since the lower end of neck 3 is closed by bottom 4 thus rendering it impossible for

any metal which may be spilled into the container to escape therefrom. In addition, 60 bottom wall 4 serves to effectually resist outward pressure of cupel A due to centrifugal force, when the device is in operation, thus eliminating all possibility of loss or breakage of the cupel while permitting the device to be swung or rotated at high speed 65 to obtain the best results in casting.

What I claim is:—

1. In a device of the character described, a downwardly tapering body provided with a depending neck closed at its lower end, and means for holding a cupel placed within the neck against movement away from the bottom of said neck. 70

2. In a device of the character described, a body provided with a depending neck, and means carried by the neck for gripping a cupel inserted into said neck. 75

3. In a device of the character described, a body provided with a depending neck, and an expansible resilient gripping ring carried by the neck and adapted to fit about and secure a cupel inserted into said neck and through the ring. 80

4. In a device of the character described, a downwardly tapering body provided with a depending neck closed at its lower end, and an expansible resilient ring carried by the neck and adapted to fit about and secure a cupel inserted into said neck and through the ring. 85

5. In a device of the character described, a downwardly tapering body provided with a depending neck closed at its lower end, said neck being provided with diametrically opposite slots, and an expansible resilient ring within the neck and provided with a radial projection extending through one of said slots, the ring being also provided with angularly disposed terminal elements projecting through the other slot. 95

6. In a device of the character described, a downwardly tapering body provided with a depending neck closed at its lower end, said neck being provided with diametrically opposite slots, and an expansible resilient ring within the neck and provided with a radial projection extending through one of said slots, the ring being also provided with angularly disposed terminal elements projecting through the other slot, the neck being provided in its inner face with an annular groove adapted for reception of the ring when the latter is expanded. 105

In testimony whereof I affix my signature.
JOHN O. BOYLE.
